Primary Examiner — Susan Bennett Hattan*Assistant Examiner* — Brett Miller(74) *Attorney, Agent, or Firm* — Blakely, Sokoloff, Taylor & Zafman LLP(57) **CLAIM**

The ornamental design for a brazier, as shown and described.

DESCRIPTION

FIG. 1 is a perspective view of a brazier, showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines depict unclaimed portions of the brazier and form no part of the claimed design.
